US0D1113881S

(12) **United States Design Patent** (10) Patent No.: **US D1,113,881 S**
(45) Date of Patent: ** Feb. 17, 2026

(54) **ANTENNA FOR DISCHARGE SENSOR**

(71) Applicant: **MITSUBISHI ELECTRIC CORPORATION**, Tokyo (JP)

(72) Inventors: **Ryota Satake**, Tokyo (JP); **Mitsuru Kubosaki**, Tokyo (JP); **Osami Kamohara**, Tokyo (JP); **Shuhei Harasaki**, Tokyo (JP)

(73) Assignee: **MITSUBISHI ELECTRIC CORPORATION**, Tokyo (JP)

(**) Term: **15 Years**

(21) Appl. No.: **29/937,005**

(22) Filed: **Apr. 11, 2024**

(30) **Foreign Application Priority Data**

Oct. 13, 2023 (JP) ..... 2023-021157 D

(57) **CLAIM**

The ornamental design for an antenna for discharge sensor as shown and described.

DESCRIPTION

FIG. 1 is a perspective view of an antenna for discharge sensor showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings are for the purpose of illustrating portions of the antenna for discharge sensor that form no part of the claimed design.

1 Claim, 7 Drawing Sheets
